UNITED STATES PATENT OFFICE.

WILLIAM M. FISCHOFF, OF CHICAGO, ILLINOIS, ASSIGNOR TO PULLMAN COUCH COMPANY, OF CHICAGO, ILLINOIS, A CORPORATION OF ILLINOIS.

SOFA-BED.

1,140,368.

Specification of Letters Patent. Patented May 25, 1915.

Application filed June 5, 1914. Serial No. 843,181.

To all whom it may concern:

Be it known that I, WILLIAM M. FISCHOFF, a citizen of the United States of America, and a resident of Chicago, county of Cook, 5 and State of Illinois, have invented certain new and useful Improvements in Sofa-Beds, of which the following is a specification.

This invention relates to convertible beds, and especially to sofa beds of the class in 10 which a foldable bed bottom is carried by an invertible or rotary seat frame.

The main objects of the invention are to provide improved means for attaching the bed bottom to the seat frame; to provide an 15 improved form of folding mechanism specially adapted for a three fold bed of this character; to mount a three fold bed bottom in an overturning seat frame so as to be free of need for locking part of the sections during the folding operation; to provide improved 20 pivotal means for mounting the seat frame and for rotating it in converting the device from one form to the other, and specially adapted to raise the seat frame as a 25 whole in turning so that an extra large size or depth of frame will clear the floor in rotating said frame; to provide an improved form of pivot plates adapted to facilitate 30 turning the seat frame from its seat position to its bed position by raising the rear edge of said frame and depressing the front edge; to provide improved means for moving the bed bottom forward and backward in the seat frame, as when the seat is inverted and 35 the bed bottom lies folded therein; to provide a supplementary movable support adapted to carry the bed bottom still farther forward so as to compensate for the limited travel of the main carriage means 40 and to accommodate bed sections of the full length for which the frame is adapted; to provide improved and co-operative locking means adapted to secure the seat frame when in its bed position, to hold the sections locked together when folded in the 45 seat frame, and to prevent the bed bottom from sliding out of its retracted or storage position when the seat frame is released for rotation to its sofa position; to provide im- 50 proved means for locking the seat frame in its sofa position; and to provide automatic means for controlling the position of the

bow-shaped spacing bars which are pivoted to the short sections.

An illustrative embodiment of this invention is shown in the accompanying drawings, in which—

Figure 1 is a side elevation of a sofa bed with the bed bottom unfolded and with the near end of the sofa frame removed to show the details of the seat frame and members associated therewith. Fig. 2 is a fragmentary plan view of a portion of the bed bottom and seat frame and shows the relative position of the leg folding and section holding members on one side of the bed. Fig. 3 is a side elevation of the seat frame in its inverted or bed position, with the bed bottom folded and locked thereon, ready for turning to the seat position. Fig. 4 is a fragmentary side view of the head connecting section and the coacting ends of the adjacent sections and means for folding the bow-shaped spacing bar associated therewith, the folded position being shown by dotted lines. Fig. 5 is a fragmentary plan view of the apron bearing edge of the seat frame in its bed position and showing the main locking mechanism and its relation to the rear end of the carriage member, the bed bottom being removed all except the side rails of the middle section. Fig. 6 is a vertical section on the line A—A of Fig. 5 and shows mainly a front elevation of the equipment shown in Fig. 5, with the fastening means in its section locking position. Fig. 7 is similar to Fig. 6, except that the fastening means is shown in its reversed or seat locking position. Fig. 8 is an enlarged fragmentary side elevation showing the reciprocatory mounting or carriage to which the middle section is secured. Fig. 9 is a cross section at B—B on Fig. 8. Fig. 10 is an enlarged view of the preferred form of pivot plates, the rotary or seat plate being shown in front in its bed position, said plates being for the left side viewed as in Fig. 6. Fig. 11 shows the same plates as Fig. 10, but with the seat plate turned half way toward its sofa position, in the direction shown by the arrow. Fig. 12 shows the same plates as Figs. 10 and 11 but with the seat plate in its sofa position. Fig. 13 is a section on the line C—C of Fig. 10. Fig. 14 is an enlarged

view of a modified form of pivot plates, the seat plate being shown in front, in its bed position, said plates being for the left side. Fig. 15 shows the same plates as Fig. 14 but 5 with the seat plate turned half way toward its sofa position, in the direction shown by the arrow. Fig. 16 shows the same plates as Figs. 14 and 15, but with the seat plate turned to its sofa position. Fig. 17 is a section 10 on the line D—D on Fig. 14. Fig. 18 is a perspective view of a slotted guide stud journaled on the seat frame plate of Figs. 16 and 17. Fig. 19 is a fragmentary plan view of the middle section and carriage. Fig. 20 shows how the bed bottom may be 15 attached directly to the main carriage member.

In the construction shown in the drawings, the sofa bed comprises the usual housing or frame 1 which includes a back 2 and ends or arms 3 and 4, in combination with a rotary seat frame 5 mounted between and supported by said ends. The seat frame on one side is adapted to serve as a seat 6 and 20 the reverse side is formed as a frame with end cross bars 5' adapted for mounting the bed bottom 7 reciprocatably thereon. The bed bottom comprises a series of foldably related sections adapted to unfold when the 25 seat frame is turned to its inverted position and the bed bottom is advanced to the position shown in Fig. 1.

The connection of seat frame to the sofa frame at each end comprises a pair of pivot 30 plates 8 and 9 of improved construction fitted with sliding pivots and guide means adapted for raising the seat frame in turning as hereinafter described, said plates being formed and adapted for inverting the 35 seat frame preferably by depressing the front edge having the apron member 10 and lifting the rear edge, and for restoring to its sofa position by a reverse movement.

The bed bottom is multi-fold in character 40 and preferably comprises three long sections 14, 15 and 16 and two short connecting sections 17 and 18 hinged together end to end in alternate position and adapted for folding together upon the under side of and 45 within the seat frame 5 with the long sections lying substantially horizontal and with the short sections disposed vertically.

The foot and middle sections may be of 50 substantially the same length, but the head section is somewhat shorter, and section 17 is somewhat shorter than section 18 whereby the head section may fold upon the middle section and the foot section upon the head section, in which position, when the bed 55 bottom is retracted, they may be locked together, as will be explained. The difference in length of the long sections is substantially equal to or somewhat greater than the thickness of the mattress and usual bedding (not 60 shown), and the same is true of the short

sections. The sections preferably have rule 65 joint connection, and constitute an open rectangular frame when unfolded within which is stretched an elastic bed spring or fabric 19.

For the purpose of mounting the bed bottom in such manner as to permit of its being drawn forward for unfolding when the seat 70 frame is inverted and so permit of unfolding the head and foot sections independently of each other, a pair of track members or 75 guide rails 20 are secured to the inner sides of the seat frame end rails 5', on which rails the bed bottom is reciprocatably mounted as by members 21 and 22, preferably having anti-friction means as will be described.

A carriage member or frame 22 is secured to each side of the middle section 15 adjacent to its rear edge for supporting the bed bottom, said carriage being movable backward and forward on said rails. Each carriage comprises a vertical flange 22' and a horizontal flange 22'' and is preferably provided on each flange 22' with a pair of flanged rollers or wheels 23 spaced apart 80 and adapted to travel on one edge of the rail and a third roller 23' disposed opposite the first two and midway between the same for coaction with the opposite edge of the rail, whereby the carriage is secured definitely to the rail in coactive relation therewith and 85 is prevented from jumping the track.

Although it may be sufficient to mount the bed bottom directly upon said carrying means 22 (as illustrated in Fig. 20) when a relatively short head section is used, it is 90 preferable to provide on each side an intermediate or supplementary carriage member 24 reciprocatable upon the first carriage member 22 in the same direction and having the bed bottom fixed thereon whereby the 95 range of reciprocatory movement may be increased to substantially the full length of the major sections and thereby compensate for the limited travel of the main carriage member. By this means, when the bed bottom is advanced, a space may be provided 100 thereby back of the middle section sufficient for unfolding a head section of the full normal length which the seat frame is adapted to accommodate. In this instance the carriage 105 22 has a longitudinal guide slot 25 in its horizontal flange 22'', and the supplementary member 24 preferably comprises an angle bar having an upwardly disposed flange 26 fixed to the side rail of the middle section 15, and an inward horizontal flange 26' to which guide means are rigidly attached, comprising a spacing block 27 somewhat thicker than said slotted flange 22' 110 to give clearance, and disposed on the lower side of flange 26', and an overlapping plate 28 disposed on the underside of said block 27 and flange 22'', said block and plate being secured rigidly together and to said flange 26', as by means 28'. Said block 27 fits 115

flange 22' to give clearance, and disposed on the lower side of flange 26', and an overlapping plate 28 disposed on the underside of said block 27 and flange 22'', said block and plate being secured rigidly together and to said flange 26', as by means 28'. Said block 27 fits 120

freely in slot 25 and a pair of rollers 29 are journaled on vertical pivots 29' fixed to flange 26' at opposite ends of block 27, and disposed in the slot 25 to prevent binding 5 and to facilitate reciprocation of carriage 24 on carriage 22.

A lock plate 30 is secured to the under side of the rear end of the side rail 15' of section 15, which plate projects rearwardly 10 and has a notch 30' to receive a coacting latch provided therefor when the bed bottom is retracted as will be described.

The front carriage 21 is secured to section 15 in a manner similar to that shown 15 by Fig. 20, and has rollers 21' spaced vertically to coact with the edges of the rail 20 when section 15 is retracted.

A pair of bow-shaped spacing bars 31 and 32 are disposed across the bed bottom between the side rails of the short sections 17 and 18 respectively. Said bars are pivoted to medial portions of said sections whereby they may be turned to lie compactly against the respective sections when the latter are folded, and to swing downward therefrom so as to give clearance for the bed spring 19 when the sections are unfolded. The head bar 31 must be raised for retracting the bed bottom so as to clear the seat member 6. In order to insure definite operation of said bow members 31 and 32 independent of manual control, automatic means are provided for each bar operable by the folding of the sections and preferably 35 comprising a link 33 pivoted at one end to the foldable major section adjacent thereto or to a fixture 34 thereon, and at its opposite end to a bracket or arm 35 fixed to said spacing bar near its pivoted end. By this 40 means the bar 31 is folded against section 17 when the head section is raised and the bar 32 is folded against section 18 when the foot section is raised, and vice versa.

In order to prevent accidental tilting of the seat frame when in its sofa position, an improved automatic lock is provided comprising a latch 37 pivoted to the rear edge of the seat frame (opposite from the apron 10), in combination with a coacting shoulder 45 or stud 38 fixed to the sofa frame 1 preferably on the right end 4. Said latch is urged normally into its locking position by any suitable means, a spring 39 being preferred. One edge 37' of the latch is cam shaped and 55 notched at 40 so as to enter into engagement with the stud 38 when the seat is turned to its sofa position. A flexible strap or loop 43, adapted to serve as a pull when grasped by the hand, is secured to the free 60 end of latch 37, by means of which the seat frame may be released and rotated by a single pull upward and forward.

Improved coactive locking means are provided adapted for simultaneous actuation 65 and control by a common manual movement

in one direction or the other, to secure the seat frame in its bed position, to secure the bed sections folded together when the bed bottom is retracted, and to secure the carriage for the bed bottom in its retracted position, said means being operable by a handle 70

45 which, when moved in one direction, locks the seat frame and releases the carriage and bed sections, and which, when reversed, locks the carriage and bed sections and releases the seat frame. Said coactive means comprises a pair of bars or shafts 46 and 47 journaled vertically on the inner side of the apron 10, said bars each being provided with a crank arm at each end, the arms 46' and 47' at the upper ends (see Fig. 7) being disposed parallelly in the same direction, and the arms 46'' and 47'' at the lower ends preferably being at an angle from each other. The arm 46'' is double in character and extends in opposite directions. The upper arms are connected by the handle link 45.

A pair of plungers 48 are mounted upon or adjacent to the lower edge of the apron 10 (Fig. 7), said plungers, when moved outwardly, being arranged to project beyond the ends of the seat frame and to enter sockets 49 provided in the arms 3 and 4 of the sofa in registry therewith, the inner ends of said plungers being pivoted to said arms 46''. 90 A pair of latch members 50 preferably in the form of bell crank levers are mounted either upon or adjacent to the lower edge of apron 10 near its ends, one arm 52 of each latch being formed and adapted to engage 95 the rearward catch plate 20 of the middle section when the bed bottom is retracted, and the other arms 53 being connected by means of links 55 to the outer end of the arm 47''. Said upper arms, when turned 100 transversely of the apron 10, and when the bed bottom is folded and retracted, overlie the adjacent end or rail 16' of the foot section and thereby the bed sections are locked 105 in their folded position. When the said bars 110 are in this position the lower arms are disposed longitudinally of apron 10 whereby two of them 46'' hold the locking plungers 48 engaged with the sofa arms 3 and 4 to prevent turning of the seat frame, while the 115 arm 47'' serves to retract the latch levers 50. One of the latches 50 opens upwardly and the other downwardly.

To better support and secure the sections in folded relation, a pair of brackets 56 are 120 secured to the bottoms of the side rails of the head section and coacting shoulders 57 are provided on the foot section, said brackets being formed at 56' to receive the shoulders 57.

Automatically operable leg means are provided for supporting the bed sections when unfolded. To this end legs 60 are pivoted to the sides of the middle section at the point 61 the projecting upper ends of said 130

legs being connected by links 62 to the rearwardly adjacent short section, whereby said legs are automatically folded and unfolded by the corresponding movements of the bed sections. The said legs have to be unfolded when the section is in its bed position. The lower ends of said legs are therefore fitted with rollers 63 in order that friction with the floor may not interfere with their operation. The foot section is provided with legs 65 and folding means 66.

The end plates on which the seat frame is pivoted are formed to raise and lower the seat frame in turning so that in its medial position the center of the frame will be raised materially above its normal position, whereby the lower edge of the frame will clear the floor when using a wider frame than would otherwise be permissible. Preferably the form of the plates is as follows: Each pair of plates (see Figs. 10 to 12 and 14 to 16) comprises a stationary plate and a movable plate, one of which is provided with a slot extending longitudinally and preferably in a substantially horizontal or somewhat upwardly bowed position. The complementary plate of each pair is provided with a cam guide member adapted to impart a predetermined movement to the seat section in turning. Each plate is provided with a projecting shoulder or pin adapted to coact with the guide member of the complementary plate. In order that the seat frame may be raised to a greater extent in turning, the pivot stud or shoulder carried by one of the plates is positioned adjacent to one end of its supporting plate whereby in rotating the seat frame the said stud is moved longitudinally of the horizontal guide member on the opposite plate and the main body of the movable plate turns upon and above said pivot stud. Preferably the guide means of each plate is in the form of a slot as shown in Figs. 10 to 13. In this instance the slot 70 in the fixed plate 9 is substantially straight and provided with an enlargement or notch 72 in its upper edge to receive the head 73 of the coacting stud 74 of the complementary plate 8. The stud 76 of plate 9 is fixed in the upper central portion of the plate. The guide means of the rotary plate 8 is in the form of a slot 78 and is disposed generally in a vertical position, its form being somewhat hook-shaped at its upper end (Fig. 10), both ends being turned toward that end of the plate in which said stud 74 is secured, and which is toward the seat apron 10. By this construction the movement of the rear edge of the seat frame in turning from the sofa position is largely forward and gradually upward during the first part of its movement until its highest point is reached, whereupon it lowers abruptly to its bed position, the reverse movement being followed in turning.

the seat frame to its sofa position. A stop shoulder 80 on plate 9 arrests plate 8 in its sofa position, and also in its bed position.

In the form of plates shown in Fig. 14, the slot 82 in the fixed plate 83 is curved upward somewhat along the center, whereby the elevation of the seat frame is increased somewhat in its intermediate position. The coacting pivot stud 84 in the rotary plate 85 is mounted adjacent to one end of said plate, whereby, in turning the seat frame, the main body of the movable plate passes over the said pivot and thereby serves very effectively to raise the seat. Said slot 82 is enlarged at 82' to admit the head of stud 84. The cam guide means on the movable plate 85 and the coacting pivot stud on the fixed plate 83 are further modified as follows: The guide means comprises a curved flange 86 turned inward along the edge of plate 85, and the coacting pivot stud 87 is slotted across its inner end or head 87' to receive said flange, whereby the movement of the plate is guided as the flange travels through the pivot slot in rotating the seat frame. Said slotted stud is preferably journaled to its support adjacent to the upper corner which is remote from the headed stud in the sofa position. By this means the seat frame in its sofa position is supported on two pairs of widely separated pivot studs at opposite ends of the frame. In the bed position one end of the movable plate is supported by the headed stud 84 adjacent to that end, and the opposite end is supported by an outwardly turned shoulder 88 on the lower edge of the stationary plate, thus providing a substantial support at widely separated points on each end of the seat frame. The curvature of the cam flange 86 is slight on the forward portion of the plate in the sofa position, and gradually grows more acute toward the rear end, whereby in turning the seat frame to the sofa position said frame is turned mainly in a somewhat forward position and then thrust backward adjacent to and somewhat under the upholstered back of the sofa during the latter part of the turning. The perforations and especially the perforated bosses shown on the plates are for mounting screws.

The sofa frame is open in front so as to facilitate interchangeability of seat frames by springing the ends 3 and 4 apart for introducing each of the main or headed pivot studs into the slot enlargements of the coacting plate respectively.

Although but one specific embodiment of the section folding and controlling means, and only two specific embodiments of the pivot plates are shown, it is to be understood that no attempt has been made to illustrate specifically all embodiments which may be used to advantage, and that some of the details of the constructions shown may

be altered or omitted without departing from the spirit of this invention as defined by the following claims.

I claim:

5. 1. In a device of the class described, a stationary member and a rotary seat frame supported thereby, in combination with a foldable bed bottom carried reciprocatably by said seat frame. 70
10. 2. In a device of the class described, a stationary member and a rotary seat frame supported thereby, in combination with a foldable bed bottom carried reciprocatably by said seat frame, and means for locking 80 said bed bottom in its retracted position.
15. 3. In a device of the class described, a stationary member and a rotary seat frame supported thereby, in combination with an extensible bed bottom carried reciprocatably by said seat frame. 85
20. 4. In a device of the class described, a stationary member and a rotary seat frame supported thereby, in combination with an extensible bed bottom movable forward and 90 backward on said frame to its bed and sofa positions respectively, and a short carriage interposed between said bed bottom and frame and movable with said bed bottom through a part of the travel of the latter, 95
25. and vertically journaled rollers coacting between said bed bottom and carriage to prevent lateral binding of the bed bottom on 100 said carriage.
30. 5. In a device of the class described, a rotary seat frame and supporting means therefore, in combination with a foldable bed bottom reciprocatably mounted on said seat frame, and locking means of reversible character formed and arranged for movement in 105 one direction to secure the bed bottom in retracted position and for movement in the reverse direction for locking the seat frame non-rotatably with respect to its said supporting means.
35. 45. 6. In a device of the class described, a stationary support member and an overturning seat frame carried thereby, in combination with a foldable bed bottom reciprocatably attached to said seat frame and coactive locking means carried by said seat frame 110
40. comprising a handle, a member adapted to engage said stationary member when the seat frame is inverted, a member adapted to engage the bed bottom when the latter is 115 retracted, and a member adapted to secure the sections when folded.
45. 7. A rotary seat frame, and a support therefor, in combination with a foldable bed bottom carried by the seat frame, said bottom comprising a section arranged and 120 mounted to reciprocate forward and backward non-turnably in the seat frame, and a rearwardly turning section joined to the back edge of the first mentioned section. 125
50. 8. A rotary seat frame, and a support 130
- therefor, in combination with a foldable bed bottom carried by the seat frame, said bottom comprising a section arranged and mounted to reciprocate forward and backward non-turnably in the seat frame, a rearwardly turning section joined to the back edge of the first mentioned section and fastening means operable to secure said bottom folded and retracted.
9. In a device of the class described, a rotary seat frame, in combination with a foldable bed bottom reciprocatably mounted thereon, locking means comprising a member adapted for securing the bed bottom in its retracted position, another member adapted for securing the sections in folded relation, and a handle for said locking members to which they are operatively connected, said locking means being formed and arranged for engaging said bed bottom and sections when the handle is moved in one direction and for releasing the same when the handle is moved in the opposite direction. 135
10. A device of the class described, comprising a stationary frame in combination with a rotary member, a foldable bed bottom secured to said rotary member, means for carrying said bed bottom forward and backward on said rotary member, and locking 140 means formed and arranged for actuation in one direction to secure the bed bottom in its retracted position on said rotary member and to secure the sections in folded relation and adapted for actuation in the opposite direction to disengage said bed bottom and sections and to lock the rotary member in fixed relation with said frame.
11. In a device of the class described, a seat member in combination with a foldable bed bottom mounted on and carried by, said seat member and carriage means secured to an intermediate bed section for reciprocating said bed bottom on said seat member, said carriage means comprising a main carriage member movable on said seat member and supplementary carriage means coactive therewith and fixed to said section for increasing the range of movement of said bed bottom, said carriage members having compact sliding relation to each other. 145
12. A rotary seat frame, a support therefor, guide means across the ends of the seat frame, a foldable bed bottom carried reciprocatably by said guide means, rearwardly projecting fastening means carried by said reciprocatory member, operative means carried by the seat frame adapted to lock with said fastening means for securing the bed bottom in its retracted position, and a handle member connected to said operative means for actuating the same. 150
13. A rotary seat frame and a support therefor, in combination with guide means disposed transversely of the seat frame, a 155

foldable bed bottom movable forward and backward on said guide means, an apron on the seat frame, a crank shaft vertically disposed and journaled upon said apron, crank arms spaced apart and adjacent to opposite ends of said shaft respectively, and a fastening member carried operatively by the apron and having connection to the lower crank arm, the upper crank arm being operable manually, said shaft when turned to one position being operative to throw the upper arm into engagement with the bed sections to hold the same folded, and the lower arm serving to throw said fastening means into engagement with the bed bottom for retaining the same in retracted position.

14. A rotary seat frame having an apron member at one edge thereof and a support for said seat frame, in combination with a foldable bed bottom reciprocatably movable on the seat frame toward and from said apron, vertically disposed manual control means journaled upon said apron, said means comprising an upper arm adapted when swung forward to overlie and secure the bed sections in folded relation, a horizontally disposed plunger carried by the seat frame adjacent to said apron and operably connected to said control means for outward movement to engage said support member, pivotal latch means carried by the seat frame adjacent to said apron and operable in one direction to engage and secure the bed bottom in its retracted position, and a link member operatively connecting said latch to said control means.

15. A rotary seat frame having an apron member and a support for said seat frame, in combination with a foldable bed bottom carried by said frame, and movable forward and backward thereon when the seat frame is in its bed position, a crank shaft journaled in vertical position upon said apron, a pair of oppositely disposed arms on said shaft, a pair of horizontally disposed plungers pivoted to the outer ends of said arms and adapted by outward movement to engage said support member, a third arm on said shaft adapted for locking the bed sections in folded relation, and means operatively connected to said shaft for securing the bed bottom in its retracted position.

16. A rotary seat frame having an apron member and a support for said seat frame, in combination with a foldable bed bottom carried by said frame, and movable forward and backward thereon when the seat frame is in its bed position, a crank shaft journaled in vertical position upon said apron, arms on said shaft, a pair of latch members pivoted to said apron and adapted by suitable actuation to lock the bed bottom in its retracted position, links connecting said latches to one of the arms on said

shaft, another of said arms being arranged to overlie and secure the bed sections in folded relation, and means operatively connected to said shaft for securing the seat frame non-rotatably respecting said support and for securing the bed sections in folded relation.

17. In a device of the class described, a rotary seat frame fitted to serve as a seat on one side and adapted for mounting a bed bottom on the opposite side in combination with guide rails secured to opposite ends of said opposite side, a foldable bed bottom having carriage means secured to opposite edges of one of the sections, and rollers journaled to said carriage means and arranged to travel on said guide rails for moving said bed bottom forward and backward.

18. In a device of the class described, a rotary seat frame and a support therefor, in combination with a foldable bed bottom carried by the seat frame and complementary coacting guide means secured to the seat frame and bed bottom respectively adapted for reciprocation of said bed bottom forward and backward in the seat frame.

19. In a device of the class described, a rotary seat frame and a support therefor, in combination with a foldable bed bottom carried by the seat frame and complementary coacting guide means secured to the seat frame and bed bottom respectively adapted for reciprocation of said bed bottom forward and backward in the seat frame and comprising at each end of the seat frame a guide rail secured to the seat frame, and a plurality of rollers secured to the bed bottom in coactive relation with the guide rail.

20. In a device of the class described, a rotary seat frame and a support therefor, in combination with a foldable bed bottom carried by the seat frame and complementary coacting guide means secured to the seat frame and bed bottom respectively adapted for reciprocation of said bed bottom forward and backward in the seat frame and comprising at each end of the seat frame a guide rail secured to the seat frame, a carriage member secured to one of the bed sections, and another carriage member reciprocatably mounted upon said rail, said carriage members being reciprocatable with respect to each other.

21. In a device of the class described, a rotary seat frame and a support therefor, in combination with a foldable bed bottom carried by the seat frame and complementary coacting guide means secured to the seat frame and bed bottom respectively adapted for reciprocation of said bed bottom forward and backward in the seat frame and comprising at each end of the seat frame a

guide rail secured to the seat frame, a pair of coacting carriage members movable one upon the other, one being secured to one of the bed sections and the other being reciprocatably mounted upon said rail, and anti-friction rollers arranged to coact between said carriage members.

22. In a device of the class described, a rotary seat frame and supporting means therefor, in combination with a reciprocatably mounted foldable bed bottom, said seat frame having guide means disposed across its ends and said bed bottom having carriage means secured adjacent to the rear edge of one of its sections for coaction with said guide means, and independent carriage means secured adjacent to the front edge of said section for coaction with said guide means when the bed bottom is retracted.

23. A foldable bed bottom, comprising a plurality of sections hinged together, a bow-shaped spacing bar disposed transversely of the bed bottom and having its ends pivotally connected to medial portions of an intermediate section, the medial portion of said spacing bar being arranged to swing down and away from the bed bottom when the latter is unfolded and to fold substantially into the same plane with its supporting section when the bed bottom is folded, a bracket projecting from the side of said spacing bar adjacent to one of its ends and at an angle from the plane of said bar, and a link connecting from the outer end of said bracket to the adjacent end of one of the adjacent sections.

24. A foldable bed bottom, comprising a short section, a second section hinged to one edge thereof, a bow-shaped spacing bar pivoted to and connecting the opposite sides of said short section, and means connecting said spacing bar and second section adapted and arranged for folding the spacing bar against the short section when said sections are folded.

25. A foldable bed bottom, comprising a short section, a second section hinged to one edge thereof, a bow-shaped spacing bar pivoted to and connecting the opposite sides of said short section, a bracket secured to said bar adjacent to one end, a second bracket secured to the second section adjacent to the first mentioned bracket, and a link connecting said brackets.

26. A bed bottom, comprising a pair of sections hinged together, a bow-shaped spacing bar pivoted at its ends to the opposite

sides of one of the sections, and means disposed between the sides of the bed bottom and operatively connecting said bar and the other section adapted for folding said bow-shaped bar against its supporting section when said sections are folded.

27. In a revoluble seat sofa bed having a seat member the rear part of which lifts and swings forward for conversion of the device to its bed form, a pair of pivot plates for said seat member one of which is provided with a guide slot disposed in a substantially horizontal position and the other of which is provided with cam guide means, and pivot members carried one by each of said plates and adapted to coact with the corresponding guide means on the opposite plate respectively, said guide means being formed and adapted to impart a backward thrust to the seat frame as it approaches its seat position and vice versa, the curvature of said guide means being greatest at or adjacent to that end which, when the seat is in its bed position, is in coactive relation with the corresponding pivot member, the opposite part of said guide means being more nearly straight.

28. In a device of the class described, a rotary seat frame and a support therefor, said seat frame being overturnable by initially raising and advancing its back part and depressing its front part in rotating the same to bed position and vice versa, said support and seat frame having coacting turning plates fitted with cam means formed near its trailing end to thrust the seat frame horizontally rearward in turning to a sofa position.

29. In a sofa bed, an overturning seat frame rotatable anti-clockwise to its bed position (as viewed in Fig. 1), in combination with a pair of complementary pivot plates secured to the sofa frame and seat frame respectively, both a guide cam means and a stud being provided on each plate, the opposite guides and studs being coactive respectively, the guide means of the turning plate being nearly fish-hook shaped and in the sofa position being disposed with its ends pointing diagonally forward and upward, the longer arm being above the shorter.

Signed at Chicago this 2nd day of June 1914.

WILLIAM M. FISCHOFF.
